UNITED STATES PATENT OFFICE.

CHARLES N. MORRISON, OF MIDLAND, MICHIGAN, ASSIGNOR TO THE DOW CHEMICAL COMPANY, OF MIDLAND, MICHIGAN, A CORPORATION OF MICHIGAN.

FURNACE.

Application filed October 11, 1919. Serial No. 330,048.

To all whom it may concern:

Be it known that I, CHARLES N. MORRISON, a citizen of the United States, and a resident of Midland, county of Midland, and State of Michigan, have invented a new and useful Improvement in Furnaces, of which the following is a specification, the principle of the invention being herein explained, and the best mode in which I have contemplated applying that principle so as to distinguish it from other inventions.

The object of the present invention is the provision of a furnace wherein the distribution of heat throughout the heating chamber proper may be effectively regulated and controlled. Other advantageous elements are incorporated in the design which may be successfully utilized in furnaces intended for widely different uses, although such device is particularly adapted to a furnace for the destructive distillation of materials, such as alcohol, for example, in the generation of ethylene, or for cracking kerosene, etc.

To the accomplishment of the foregoing and related ends, the invention, then, consists of the means hereinafter fully described and particularly pointed out in the claims, the annexed drawing and the following description setting forth in detail certain mechanism embodying the invention, such disclosed means constituting, however, but several of various mechanical forms in which the principle of the invention may be used.

In said annexed drawing:—

Fig. 1 is a plan view of one construction of furnace embodying my present improvements; Fig. 2 is a central vertical section of the same taken on the plane indicated by the line 2—2, Fig. 1; Fig. 3 is a perspective view of an element of such furnace; Fig. 4 is a horizontal section of a modified form of construction; Fig. 5 is a vertical section of such modified form, the plane of the section being indicated by the line 5—5, Fig. 4; and Fig. 6 is a transverse section taken on the plane indicated by the line 6—6, Fig. 4, the part of the furnace here shown being substantially identical in the two types illustrated in Figs. 1 and 2, and 4 and 5, respectively.

The principal difference between the two types of construction found in the drawings is in the form of the container or chamber

through which the material to be treated, where liquid in character, is passed. Thus in the case of the construction shown in Figs. 1 and 2, this container is in the form of a flat rectangular metal box 1 provided on its upper face with one or more inlet connections 2, and similarly on its lower face with one or more outlet connections 3. The interior of such chamber is preferably filled with suitable material 4, a portion of one side wall being broken away in Fig. 3 the better to show such material. The latter may be simply of inert character sufficiently broken or fragmentary to thoroughly distribute the liquid entering through connections 2, or such material may be of a catalytic character, depending upon the particular operation in which the furnace is being employed.

As shown in Figs. 1 and 2, a plurality of such containers 1 are mounted in laterally spaced relation in the heating chamber 5 of the furnace. A pit 6 is preferably provided below such chamber 5 so as to render possible access to the containers from below without necessarily removing the same. The spaces between adjacent containers are of course sealed off above, so as to entirely enclose the sides of the heating chamber.

The combustion chamber 7 will take on various forms, depending upon the kind of fuel used, the one illustrated being designed for either gaseous or hydrocarbon fuel which will be supplied by means of a suitable burner (not shown) projecting through an opening 8 in the further end wall of the chamber. Resting on the floor of chamber 7 directly in front of such opening 8 is a deflector 9 for securing the full effect of the blast from the burner, while an adjustable baffle 10 depends from the roof of the chamber at a point between such deflector and a perforated wall 11 that is interposed between said chamber and the heating chamber in which the containers 1 are located. Said wall 11 is conveniently built of brick checkerwork, so as to leave a series of openings aligned with each of the spaces between the several containers 1. Beyond the containers the heating chamber 5 is divided into several areas of uniform size by thin separating webs 12, the relation of which is perhaps best shown in Fig. 6 in connection with the modified construction of Figs. 4 and 5. Leading from the center of each such

area or zone is a separate exit flue 13 that connects with a common stack 14, the effect of the webs being to confine and at the same time equalize the draft through the respective flues. In addition to a baffle plate 15 in such stack, each such flue 13 is provided with an independent damper 16 whereby it will be seen that the draft may be accurately controlled through each of the zones defined by the walls 12 at the farther end of the heating chamber.

At the same time, by means of the baffle 10 and checkerwork character of wall 11, an equable distribution of heat, both crosswise and vertically, may be secured in the heating chamber, thus insuring uniform results not only in each of the containers 1, but throughout each individual container.

In the modified construction shown in Figs. 4 and 5, the heating chamber 20 is much reduced in longitudinal extent, due to the fact that the containers through which the material to be treated is passed consists simply of a series of vertical pipes 21 ranged transversely of such chamber in front of a checkerwork wall 22 similar to wall 11 in the first described construction. The general arrangement of the combustion chamber 23, with its deflector 24 and baffle 25, is so similar as to require no separate description. Likewise it will be observed that the portion of the heating chamber lying beyond the ducts 21 is divided into several areas or zones by separating partitions or webs 26, just as in the first described construction, each such area having its separate flue 27 whereby it is connected with a common stack 28.

It will be understood that in either type of construction successive series of containers, whether of the box-like form of Figs. 1 and 2, or of the simple pipe form of Figs. 4 and 5, may be grouped in several heating chambers, each under separate heat control, so that the material, such as alcohol or kerosene, to be treated may be circulated successively from one set of such containers to the next, approaching gradually the hottest heating chamber. It will also be understood that in place of containers for a liquid to be destructively distilled or cracked, the space in the heating chamber may be occupied by any suitable article requiring to be heat-treated. The equable distribution of heat secured throughout such chamber will be just as advantageous in heat-treating metal parts or for various other uses, as for heating containers of the character hereinbefore referred to.

As shown in Fig. 5, the pipes 21 may have chain 30 depending therein in order to break up the stream of liquid passing therethrough.

Other modes of applying the principle of my invention may be employed instead of

the one explained, change being made as regards the mechanism herein disclosed, provided the means stated by any of the following claims or the equivalent of such stated means be employed.

I therefore particularly point out and distinctly claim as my invention:—

1. In a furnace for destructive distillation, the combination of a combustion chamber; a heating chamber leading therefrom; a plurality of containers in said heating chamber through which the material to be treated is passed, said containers being disposed in parallel relation relatively to the flow of heating gases; a stack; and a plurality of flues connecting the farther end of said heating chamber with said stack, said flues leading from points in such end spaced in each of two transverse directions.

2. In a furnace for destructive distillation, the combination of a combustion chamber; a heating chamber leading therefrom; a plurality of containers in said heating chamber through which the material to be treated is passed, said containers being disposed in parallel relation relatively to the flow of heating gases; a stack; a plurality of flues connecting the farther end of said heating chamber with said stack, said flues being likewise in parallel relation and leading from points in such end spaced in each of two transverse directions; and independent dampers for said flues.

3. In a furnace for destructive distillation, the combination of a combustion chamber; a heating chamber leading therefrom; a plurality of containers in said heating chamber through which the material to be treated is passed, said containers being disposed in parallel relation relatively to the flow of heating gases; a checkerwork wall interposed between said chambers; a stack; a plurality of flues connecting the farther end of said heating chamber with said stack, said flues being likewise in parallel relation and leading from points in such end spaced in each of two transverse directions; and independent dampers for said flues.

4. In a furnace for destructive distillation, the combination of a combustion chamber; a heating chamber leading horizontally therefrom; a checker-work wall interposed between said chambers; a plurality of containers in said heating chamber through which the material to be treated is passed, said containers to be aligned with the openings in said wall; a deflector on the floor of said furnace chamber; a baffle depending from the roof of said furnace chamber between said deflector and said wall; a stack; and a plurality of flues connecting said heating chamber with said stack.

5. In a furnace for destructive distillation the combination of a combustion chamber; a heating chamber leading horizontally

thereform; a checker-work wall interposed between said chambers; webs dividing up the end of said heating chamber opposite said wall into approximately equal spaces or areas; a stack; and a plurality of flues independently connecting said areas with said stack.

6. In a furnace for destructive distillation, the combination of a combustion chamber; a heating chamber leading horizontally therefrom; a checker-work wall interposed between said chambers; webs dividing up

the end of said heating chamber opposite said wall into approximately equal spaces or areas; a stack; a plurality of flues independently connecting said areas with said stack; and a plurality of elongated rectangular box-like liquid containers, with exterior inlet and outlet connections, disposed horizontally of said heating chamber. 15

Signed by me, this 8th day of October, 1919.

CHARLES N. MORRISON.
